LIFTING AND TOWING SLING HITCH FOR VEHICLES

Gerald E. Holmes, Chattanooga, Tenn.

Application February 21, 1958, Serial No. 49,745

Term of patent 14 years

(Cl. D41—1)

Figure 1 is a perspective view of the lifting and towing sling hitch for vehicles, showing my new design.

Figure 2 is a side elevation of the lifting and towing sling hitch for vehicles.

I claim:

The ornamental design for a lifting and towing sling hitch for vehicles, as shown.
